UNITED STATES PATENT OFFICE.

RUDOLF WALKER, OF VIENNA, AUSTRIA.

FUEL-FEED PUMP FOR INTERNAL-COMBUSTION ENGINES.

Application filed January 25, 1924. Serial No. 688,528.

To all whom it may concern:

Be it known that I, RUDOLF WALKER, a subject of the Kingdom of Great Britain, residing at XI. Simmeringer Hauptstrasse 38-40, Vienna, Austria, have invented Improvements in Fuel-Feed Pumps for Internal-Combustion Engines (for which an application was filed in Austria, Sept. 4, 1922, and in Germany Sept. 9, 1922), of which the following is a specification.

This invention has for its object to provide an improved fuel feed pump for internal combustion engines of the type wherein a freely movable suction valve is arranged on the fuel pump piston. In an improved fuel pump according to this invention the suction valve is operated by the pump piston, and for this purpose the suction valve of the pump is arranged to be moved or dragged along by the pump piston in the suction and delivery strokes of the latter, whereby the suction valve is respectively opened and maintained in its opened position, and closed and maintained in its closed position. This manner of operating the suction valve allows of achieving an exact measurement and regulation of the delivery volume of the pump.

The opening and closing of the suction valve is effected positively by the motion of the pump piston by the fact that the suction valve opposes resistance to its own movement, and this resistance is overcome by the movement of the pump piston.

In a preferred constructional form of the improved pump the pump piston, in its suction stroke, engages the suction valve in its open position with a stop, and carries or drags it along in its opened position positively to the end of the pump piston stroke. In the compression stroke of the pump piston the engagement between the said stop and the pump piston is undone, whereupon the suction valve is first closed, and then whilst in its closed position it is carried or dragged to the other end of the stroke of the pump piston.

The accompanying drawings illustrate a constructional example of the improved fuel pump according to this invention, wherein the suction valve mounted in the pump piston is operated positively by the motion of the pump piston. Referring to the figures in the drawing—

Figure 1 is a vertical sectional view of a

fuel feed pump constructed in accordance with the invention.

Figure 2 is a transverse sectional view through the pump cylinder and piston in the plane of the suction valve rod engaging clip. 60

Figure 3 is a fragmentary elevation, partly in section, of the pump piston removed from the cylinder.

In the illustrated example, the fuel pump piston 2 working in the fuel pump cylinder 1 contains the suction valve 3 of the pump; the delivery valve 4 of the pump being mounted in the pump cylinder 1. The delivery valve 4 is automatic, whereas the suction valve 3 is operated mechanically. 65

The control of the suction valve 3 is effected by the to-and-fro motion of the pump piston 2. The pump piston is driven by means of a cam 5 which co-operates with an antifriction roller 6 suspended from the pump piston by means of a lever 7 in such a manner that the pump piston is moved downwards by the cam 5 in order to make its suction stroke, whereas its compression is effected automatically by means of a spring 8 acting upon the pump piston. The opening of the suction valve 3 is produced by the arrangement that the suction valve rod 9 is fixed in position relatively to the pump piston by means of a jamming device 85 until this jamming or braking action is overcome by the operation of a stop and the suction valve in its opened condition is carried along by the piston.

In the illustrated example the valve rod 9 extends through the pump piston 2 down to a point 14 of the pump casing 1 where access can be had to the said point from the outside. The valve rod which carries a stop 11 at the said point, is fixed in a spring clip 10 mounted in the stationary cylinder 1 (Fig. 2). The stop 11 for the pump piston 2 is preferably constructed in the form of a nut on the valve rod, and it causes the valve 3 to be carried along by the pump piston. The amount of "play" between the stop 11 and the piston 2 determines the amount of lift of the valve 3. This lift can be adjusted by adjusting the stop 11. The closing of the suction valve during the delivery stroke of the pump piston is due to the fact that by reason of the valve rod 9 being clipped by the clip 10 the piston effects the closing of the valve by moving in the upward direction away from the stop 11. 105

110

In order to obtain a complete filling of the pump suction chamber and a uniform delivery at every speed, the pump piston 2 is constructed, in the illustrated constructional example, as a stepped piston the larger stage 15 of which is utilized as a suction stage during the upstroke of the pump piston with the result that the fuel is sucked from the storage casing 13 through suction passages 14 into the pump suction chamber 16, whereas in the down stroke of the piston the fuel is delivered through the open suction valve 3 into the delivery chamber of the pump. In the down stroke, the stop 11 acts as a device for closing the suction chamber of the pump. Owing to the sucking action of the larger stage so much oil is delivered in excess that a complete filling of the pump, even at its highest speed, is assured.

What I claim is:

1. A fuel pump for internal combustion engines including a cylinder, a pump piston having passages therein, a suction valve in said piston, a stem carried by the valve and extending through one of the passages in the piston to another of the passages through which latter the stem is exteriorly accessible, a stop carried by the accessible portion of the valve stem, and a retaining device co-operating with the stem whereby the suction valve, on the suction and pressure strokes

of the piston, is opened and closed and carried along in opened and closed positions with the piston.

2. A fuel pump as claimed in claim 1 characterized by the provision of a fuel reservoir associated with the cylinder and an opening in the latter communicating with the second mentioned passage in the piston.

3. A fuel pump as claimed in claim 1 characterized in that the retaining device consists of a stationary resilient clamping device co-operating with the valve stem.

4. A fuel pump as claimed in claim 1 characterized in that the stop carried by the valve stem is adjustable.

5. A fuel pump as claimed in claim 1 characterized by the provision of a stepped piston having openings therein communicating with the passages, the larger step of the piston forcing the fluid drawn in through said openings then into the suction passage of the piston on the suction stroke of the small step, the lug closing the suction passage during the last mentioned suction stroke.

In witness whereof I have hereunto signed my name in the presence of two subscribing witnesses.

RUDOLF WALKER.
